United States Patent Office

Des. 217,988
Patented July 7, 1970

217,988

COLOR ANALYZER INSTRUMENT

James H. Casterlin, Binghamton, N.Y., assignor to Kollmorgen Corporation, Holyoke, Mass., a corporation of New York

Filed May 16, 1969, Ser. No. 17,189

Term of patent 7 years

Int. Cl. D10—11

U.S. Cl. D61—1

FIG. 1

FIG. 2

FIG. 3

FIG. 1 is a perspective view of a color analyzer instrument, showing my new design;

FIG. 2 is a top view thereof; and

FIG. 3 is a front elevational view thereof.

The undisclosed rear is substantially plain.

I claim:

The ornamental design for a color analyzer instrument, substantially as shown and described.
